Primary Examiner — Nicole C Shiflet*Assistant Examiner* — Yen Le Southwood(74) *Attorney, Agent, or Firm* — Sterne, Kessler, Goldstein & Fox P.L.L.C.(57) **CLAIM**

The ornamental design for cutlery, as shown and described.

DESCRIPTION

FIG. 1 is a top front perspective view of cutlery showing the claimed design;

FIG. 2 is a bottom front perspective view thereof;

FIG. 3 is a bottom rear perspective view thereof;

FIG. 4 is a top rear perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

1 Claim, 5 Drawing Sheets(56)
